UNITED STATES PATENT OFFICE.

RUFUS H. HURLBUT, OF SUDBURY, MASSACHUSETTS.

CUTTING-OFF MECHANISM.

SPECIFICATION forming part of Letters Patent No. 678,569, dated July 16, 1901.

Application filed November 22, 1900. Serial No. 37,352. (No model.)

To all whom it may concern:

Be it known that I, RUFUS H. HURLBUT, of Sudbury, in the county of Middlesex and State of Massachusetts, have invented certain new 5 and useful Improvements in Cutting-Off Machines, of which the following is a specification.

My invention relates to that class of cutting-off machines in which a revoluble hollow 10 mandrel holds the material to be cut off and a tool-carriage is so connected to a variable-speed driving apparatus that the movement of the tool toward the axial line of the mandrel increases the speed of said mandrel, so as to 15 present to the cutting edge of the tool a substantially even speed of the material being worked.

My present invention is designed to provide a more simple and reliable connection of the 20 working parts of the machine; and it consists of improvements which are fully set forth in this specification and the drawings therewith, of which—

Figure 1 is a plan; Fig. 2, a view from the 25 cutting end of the machine; Fig. 3, a side view; Fig. 4, a section on line 4-4 of Fig. 3; Fig. 5, a detail showing the stop movement; Fig. 6, a detail showing the gear connections of the driving mechanism.

30 The same letters and figures refer to like parts in all the drawings.

On a suitable frame A is mounted a hollow mandrel revoluble in bearings C C.

B represents a shaft contained in the holding 35 mandrel and being operated on by cutting-tools, as seen in Fig. 2. Motion is imparted to said mandrel as follows: Power is applied through belts to the pulleys D D', so that they revolve in opposite directions. Each 40 is attached to a shaft E E', on the opposite end of which is mounted a friction-wheel F F'. The shafts E E' are mounted in sleeves which are adapted to slide longitudinally in ways or bosses G G', attached to the frame 45 of the machine. (See Fig. 4.) The friction-wheels F F' run between two disks H H', mounted the one on shaft J, the other, H', on a sleeve L about said shaft. (See Fig. 6.) The sleeve L carries disk H' and also a pinion M, which meshes with the large gear O upon the hollow mandrel. As the disk H re-

volves in the opposite direction from H', it is necessary to connect it by intermediate gearing to gear O, which is done by extending the shaft J through the sleeve L and mounting thereon the gear N, which meshes with a similar gear N' on a sleeve which carries a gear M', engaging with gear O and of the same size as gear M, which also engages with gear O upon the mandrel.

In Fig. 2 are seen the cutting-tools P P', operating upon opposite sides of the bar B. These tools are clamped in the tool-blocks R R', which slide in ways at right angles to the axis of the mandrel and are moved simultaneously as follows: The shaft J, Fig. 6, which carries the disk H, extends beyond the frame of the machine and carries a cone-pulley S, Fig. 1, from which a belt runs to cone-pulley S' upon one end of a shaft T, which 70 extends from end to end of the machine outside the frame and carries upon its other end a worm V, Fig. 2, which engages with the gear W, mounted upon a shaft X, which is at right angles to the frame of the machine and which 75 carries a worm 1, which engages with gear 2 upon shaft 3, which also carries pinion 4. This pinion 4 engages with two racks 5 and 6—one above and one below—which are attached by arms 7 and 8, respectively, to the sliding tool-blocks R R'. Thus it will be seen that by the revolution of the shaft J motion is transmitted to the tools P P', thereby feeding them simultaneously toward the center of the shaft B being operated upon.

The speed of the revolving mandrel is varied and controlled by the distance of the tools from its central axis, as follows: To one of the tool-blocks R' is attached a connecting-bar 9, whose opposite end is pivoted to a 90 crank-arm 10 upon a shaft 11, hung in brackets 12 12 from the frame of the machine and parallel therewith. (See Fig. 1.) Upon the opposite end of the shaft is mounted a crank-arm 13, from which a connecting-bar 14 is attached to the sliding frame 15, which is attached to and controls the shaft E of the friction-wheel F. The shaft E', carrying the other friction-wheel F', is controlled by a similar sliding frame 16. Between these frames 15 and 16 is a pinion 17, mounted on a stud attached to the frame of the machine. This

pinion engages with a rack on each of said frames, so that the motion imparted to frame 15 is communicated to 16, but in an opposite direction. By this it will be seen that the 5 position of the tool-carriage R' controls the distance of the friction-wheels F F' from the center of the disks H H', and consequently the speed of the mandrel, and as the tools approach the axis of the mandrel the friction- 10 wheels approach the center of the disks, and the speed of the mandrel is increased accordingly.

The means provided for disengaging the 15 feed of the cutting-tools and bringing them back from the central axis of the mandrel is as follows: The shaft X, carrying worm 1 and gear W, and also the adjacent end of shaft T are mounted in bearings upon a block 18, which is pivoted to the main frame at 19 and 20 held in working position by a latch 20, Fig. 5, a spring 27, pressing against a stud 28, serving to hold the latch in engagement until forced away, as hereinafter described. The shaft 3, carrying gear 2 and pinion 4, is required to make only a partial revolution in 25 any case to give the necessary throw to the tool-blocks R and R'. A stud 21, attached to a wheel on shaft 3, is adjusted in such a position that as the tools approach the central axis of the mandrel it (the stud) engages 30 a lever 22, which is attached to the catch 20 and throws the latch out of engagement with its latch 23 and allows the block 18, with all 35 its superincumbent gearing, to drop far enough to disengage worm 1 from its gear 2. This movement at one end of the shaft T is provided for as to its bearing 24 at the other end by being pivoted so as to allow a slight angular motion. As the worm-wheel 1 is 40 disengaged from its gear 2 the tools are automatically drawn back from the central axis by a weight 26, attached by a cord to lever 45 and hung as shown.

A special feature of my invention is the 45 connection of the two tool-carriages with each other by racks and an intermediate pinion and also the connection of the friction-wheel carriers by the same device.

By the use of a rack instead of the usual 50 cross feed-screws on the tool-carriage I save much time in reversing the tools, and the same device is applicable to a single tool-machine.

I do not claim anything shown or described

in Letters Patent No. 490,426, dated January 24, 1893; but 55
I claim—

1. In a machine of the character described, a revoluble mandrel, a tool-carriage adapted to slide at right angles to the axial line of said mandrel, a rack connecting therewith, a pinion meshing into said rack, mechanism for driving said pinion and thereby feeding said tool-carriage toward the axial line of the mandrel, in combination with means for disengaging said driving mechanism from said pinion 60 and mechanism whereby said pinion when disengaged will be automatically turned on its axis in a reversed direction thereby bringing the tool-carriage away from the axial line of the mandrel substantially as described. 65

2. In a machine of the character described, in combination with a revoluble mandrel, two tool-carriages adapted to move at right angles to the axial line of said mandrel, racks attached to each of said carriages, an intermediate pinion meshing with both racks, and mechanism for operating said pinion, consisting of a shaft carrying said pinion, another shaft parallel with said pinion-shaft and driven from the mandrel-driving mechanism, 70 a third shaft at right angles to the two shafts mentioned and connected to each by worm-gearing, arranged and to operate substantially as herein set forth. 75

3. In a machine of the character described 80 the following mechanism for communicating the motion of the tool-carriers to the speed-varying mechanism, viz: a rocker-shaft, two arms rigidly attached to the same at or near the opposite ends thereof, connecting-bars 90 pivotally attached to said arms, one of said bars being attached to the tool-carriage and the other to one of the sliding frames which carries one of the friction-wheels, whereby the motion of the tool-carriage toward the axial 95 line of the mandrel operates to move the friction-wheels toward the center of the disk thus accelerating the movement of the mandrel substantially as shown and described.

In testimony whereof I have affixed my signature in presence of two witnesses. 100

RUFUS H. HURLBUT.
